FLUID-OPERATED LIFT

Walter J. Maytham, Jr., Wilmette, Ill.

Application April 20, 1943, Serial No. 483,765

14 Claims. (Cl. 187—1)

This invention relates to fluid-operated lifts, and more particularly to a novel construction and arrangement and control therefor which lends itself for practical embodiment in a stair-elevator structure wherein individual lifts are adapted to be associated with each step of a conventional stairway, so that a passenger may be conveniently raised from one floor of a building to an upper floor.

The lift structures embodying the present invention, while not exclusively so, are especially suitable for embodiment in existing building structures that are of such nature that a passenger elevator structure cannot conveniently or practically be embodied therein. More particularly the invention is intended to be utilized in connection with stairways in buildings, such as residences, apartments, hotels, hospitals and various institutions. It is especially suitable for use in buildings when it is necessary or desirable for the convenience of certain occupants or patients whose physical condition is such as to preclude their climbing of stairs. It will be recognized that in many buildings, and particularly in residences, it is not usually practical to install a conventional passenger elevator, due to room sizes and arrangements in the building. Moreover the matter of cost is an important factor, in addition to the difficulty which would be encountered in providing suitable openings to the elevator at the different floors of the building or residence.

One of the objects of the present invention is to provide a novel stair elevator structure which lends itself to practical embodiment in a stairway in residences and other buildings and by virtue of which a passenger may be conveniently elevated from one floor to another by merely taking a series of short forward steps.

Another object is to provide a novel stair elevator of the character indicated wherein individual fluid operated lifts are associated with each step of a conventional stairway and wherein each of the lifts are automatically operated in response to the weight of the passenger.

A further object is to provide a novel stair elevator characterized by the provision of separate fluid operated lifts, and wherein the lifts are rendered automatically operable in response to the weight of a passenger thereon, to dispose the supporting platform of the lift at a level substantially in horizontal alignment with the horizontal upper surface of the next adjacent upper step of the stair.

Still another object is to provide a novel stair

elevator of the character indicated which is simple in construction, efficient in operation and economical to manufacture and install in a conventional stairway structure of a residence or other building.

Other objects and advantages of this invention will be apparent from the following description taken in connection with the accompanying drawing, in which

10 Figure 1 is a fragmentary, diagrammatic, side elevational view of a portion of a stair provided with fluid lifts embodying the present invention.

15 Figure 2 is a vertical section through the steps of a stair and one of the lift devices embodying the present invention, with the control mechanism thereof shown in a normal inoperative position of adjustment.

20 Figure 3 is a vertical sectional view through a portion of the control mechanism of the lift, taken substantially as indicated at line 3—3 on Figure 2.

25 Figure 4 is a fragmentary vertical sectional view of a portion of the lift and control mechanism, with the control mechanism in an actuated position, preparatory to operating the lift.

Figure 5 is a fragmentary vertical sectional view through the lift and control mechanism of a modified form.

30 It is to be understood that the lift devices embodying the present invention may be of a type for operation as a pneumatic lift from a source of compressed air, or may be operated as a hydraulic lift by a source of liquid under pressure. I have herein shown and described a construction of lift adapted to be operated by compressed air.

35 The stairway indicated generally at 10 is of conventional form and includes a series of horizontal steps 11 joined together by vertically disposed risers 12. Disposed beneath each step is a fluid operated lift indicated generally at 14, and the lift associated with the respective steps are connected in series relation by a single conduit 15, to a source of compressed air, which may be located at some convenient place in the building.

40 Each lift device includes an upright cylinder 16 closed at its upper end by a head 17, which is threaded on the exterior of the cylinder. The head 17 is formed with a laterally and forwardly extending flange 19 adapted to abut against the backside of the adjacent riser, and an upstanding bracket 20 adapted to seat against the underside of the rearward portion of the step 11. The flange 19 and bracket 20 are adapted to

be connected rigidly to the riser and step respectively by bolts 21. The step 11, immediately above the cylinder, is provided with an elongated rectangular opening 23 in which is normally seated a platform or tread 24, which preferably is of a size to conveniently support a person thereon.

The platform is rigidly secured to a flanged fitting 26, which in turn is rigidly connected to the upper end of a piston rod 27, the lower end of the piston rod being connected to a piston 28, snugly fitting the inner wall of the cylinder 16, and normally disposed at the lower end of the cylinder, as seen in Figure 2 of the drawing. The piston rod is guided at its upper end in a bearing 30 formed as an integral part of the head 17. When the piston 28 is moved upwardly, the platform 24 moves therewith as a unit, and it is to be understood that the stroke of the piston is such that the platform in its elevated position will be disposed substantially flush with the horizontal upper surface of the next upper step 11 of the stairway, as seen in Figure 1 of the drawing, and when disposed in its lowered position, it is substantially as seen in Figure 2 of the drawing, with the supporting surface thereof disposed just slightly above the upper surface of the step 11. The amount that the supporting surface of the platform projects above the step need only be a small fraction of an inch so as to permit depression of the platform and the cylinder by the weight of a person thereon, to initiate the operation of control mechanism to be presently described.

To preclude rotation or turning of the platform or tread 24, about the axis of the cylinder, so as to always insure that the platform will telescope into registration with the opening 23 of the step, I provide suitable guide means for the piston rod. For this purpose the piston rod is provided with a pair of diametrically opposite, longitudinally extending grooves 32, into which project or extend the terminal end portions of screws 34 carried in the bearing 30. It will be noted that the upper end of the grooves terminate substantially flush with the upper end of the bearing 30 in the normal inoperative position of the lift, and when the platform and piston commence to move vertically, the grooves 32, serve as atmospheric vents to permit escape of the air in the cylinder above the piston. The relationship of the upper ends of the grooves to the bearing 30 is such that in the normal inoperative or lowered position of the platform and piston, the grooves are substantially closed so as to preclude the entrance of dust or dirt, or other foreign matter, within the chamber of the cylinder.

The lower end of the cylinder 16 is closed by a bottom member 36, in the form of a casting, to which is connected at one end a casting 37, which castings together serve to enclose suitable control mechanism. The casting 36 is threaded onto the exterior of the lower end of the cylinder, and is provided with an inlet duct 38 and an outlet duct 39, communicating with the interior of the cylinder below the piston 28, the opposite ends of the ducts opening into a cylindrical bore or chamber 40 provided in the cast bottom member 36.

Slidably guided in the bore 40 is a main control valve 41, provided with axially spaced-apart, peripheral grooves 42 and 43, adapted to be selectively registered with the respective ducts 38 and 39. The lower side of the bore 40 is pro-

vided with a port 45 which provides communication between the bore 40 and a fluid supply duct 46, which terminates at opposite ends in pilot valve chambers 47 and 48 in the castings 36 and 37, respectively. The bore 40 is provided with a laterally extending port 49, located in spaced-apart vertical alignment with the outlet duct 39, and serves to provide for the discharge of the compressed air in the cylinder below piston 28, to atmosphere when the main valve 41 is moved to the position seen in Figure 2 of the drawing, with its peripheral groove 43 disposed in registration with the outlet duct 39 and the port 49.

The opposite ends of the chamber 40 are provided with atmospheric vents 51 and 52 so as to permit the main valve 41 to be freely moved axially within the bore 40 as will hereafter be described.

In the pilot valve chamber 47 is a valve port 54 which provides communication between the chamber 47 and the right hand end of the bore 40. The valve port 54 is controlled by a valve 55, which is normally urged to closed position by a coil spring 56. Connected to the upper end of the valve 55 is an operating member 58, which projects through the bottom casting 36 and extends a short distance upwardly into the bottom of the chamber of the cylinder 16, in position to be engaged by the bottom of the piston 28. It is to be understood that the spring 56 is of sufficient tension as to normally maintain the valve 55 seated, and in addition, through the operating member 58, serves to support the piston 28 together with the rod 27, and platform 24 in the position seen in Figure 2 of the drawing.

The pilot valve chamber 48 is provided with a port 60 which provides communication between the chamber 48 and the left-hand end of the bore 40 of the control mechanism. The port 60 is normally closed by a valve element 61 to which is connected the lower end of an operating rod 62. The upper end of said rod is guided in an aperture in a flange of the cylinder head 17, and terminates in position to abut against one end of a lever 63, which is pivoted at 64 on the bracket 20. The opposite end of the lever 63 normally abuts against a headed control button 66, projecting downwardly through the top of the cylinder head 17, with the stem portion extending a short distance below said head, into the chamber of the cylinder 16, in position to be engaged by the head of the piston 28. The pilot valve 61 is normally held closed and the lever 63 and connecting rod 62 are normally held in the position seen in Figure 2 of the drawing by means of a coil spring 68.

The end casting 37 is provided with a threaded opening 70, communicating with pilot valve chamber 48, and serving to receive a T-shaped fitting 71, the ends of which fitting are connected to the pipes 15, to a source of compressed air, so that the source of compressed air is at all times admitted into the duct 46, and pilot valve chambers 47 and 48, available for actuating the main valve 41, incident to operation of either of the pilot valves 55 or 61.

Operation

When a person steps on the platform or tread 24, the platform, together with the piston rod 27 and piston 28 are depressed a slight amount, moving the operating member 58 in a downward direction to open the pilot valve 55, thereby ad-

mitting compressed air through the port 54 to react against the end of the main valve 40, to move the latter from the position seen in Figure 2 to the position seen in Figure 4 of the drawing. The air normally within the left-hand end of the bore 40, prior to such movement of the main valve, is discharged to atmosphere through the vent 52. When this adjustment of the main valve 41 takes place, the compressed air is then admitted through the port 45 into the registered peripheral groove 43, and into the inlet duct 38, and the bottom of the cylinder 16, below piston 28, causing the platform 24, with the person thereon, to move in an upwardly direction. Immediately after such upward movement takes place, the operating member 58 is disengaged so that the pilot valve 55 is again closed.

When the platform 24 approaches a position, substantially flush with the upper horizontal surface of the next upper step, as seen in Figure 1 of the drawing, the upper surface of the piston 28 engages the lower end of the button 66, and moves the lever 63, so as to depress the rod 62 to cause opening of the pilot valve 61, at which time compressed air is admitted through the port 60, to react on the left-hand end of the main valve 41, and move the latter from the position seen in Figure 4 to the position seen in Figure 1 of the drawing, and the air at the right-hand end of the main valve 41 is permitted to discharge freely to atmosphere through the vent opening 51. When the main valve moves to the position seen in Figure 2, the source of compressed air supplied through the inlet duct 38 is shut off, and the outlet duct 39 has registered therewith the peripheral groove 43 of the valve element 41, which groove is also in turn in registration with the atmospheric duct 49, so that the compressed air within the cylinder 16, beneath the piston 28, is permitted to discharge to atmosphere and the piston 28, rod 27 and platform 24 are permitted to move downwardly to the position seen in Figure 2 of the drawing, at which position the cycle of operation may be repeated.

The speed of raising and lowering of the platform 24, together with the piston 28, may be varied by adjustment of valve members 72 as seen in Figure 3 of the drawing, which serve to vary the effective cross-sectional area of the inlet and outlet ducts 38 and 39.

In the modified construction shown in Figure 5 of the drawing, the control mechanism is located substantially at the side of the main cylinder 16a in order to reduce to a minimum the overall height of the lift device. In this construction the control mechanism includes a housing member 80 suitably connected to a laterally extending cast portion 81 which is formed integrally with the cylinder bottom 36a. The extension portion 81 and bottom 36a are formed with a single combination inlet and outlet duct 82 in which there is disposed an inlet ball check valve 83 and an outlet ball check valve 84, which valves are arranged in opposite relation for controlling, respectively, the inlet flow and outlet flow of the air through the duct 82. One end of the duct 82, as may be clearly seen in Figure 5 of the drawing, opens into the lower end of the chamber of the cylinder 16a, beneath the piston 28a, and the opposite end of the duct opens into a chamber 85 of the housing 80, in which there is mounted a dual valve arrangement including pilot valves 86 and 87 disposed in opposed relation to each other for controlling, respectively, ports 88 and 89 at opposite ends of the chamber 85.

The stem portion which connects the dual valves 86 and 87 is provided with an annular shoulder 90, having oppositely beveled faces with which cooperate a pair of spring-pressed ball detents 92. These detents tend to cause movement of the dual valve elements with a snap action and serve to yieldingly maintain said pilot valve elements at either of their two positions of adjustment, namely, with the valve 86 seated 10 and the valve 87 in open position, or with the valve 87 seated and the valve 86 in open position. The lower end of the chamber 85 through port 88 communicates with a duct 94, the outer end of which duct is threaded for receiving a pipe fitting 71, connected in series with the pipes 15, to a source of compressed air supply. The upper end of the valve 87 is formed with an upstanding lug 87a to which is connected the lower end of a spring connecting rod 97. The upper end 20 of the rod is connected to a lever 63a, pivoted at 64a on the bracket 20a. The opposite end of the lever cooperates with an operating button 66a slidably seated in the upper end of the head 17a of the cylinder.

Vertically movable in a boss 98 formed integrally with the bracket 20a is a headed plunger 99 around which is disposed a coil spring 100, reacting between the head of the plunger and the boss 98, and with the head of the plunger 30 positioned to be engaged by the underside of the platform 24a.

Operation

Normally the platform 24a is in the position indicated in dotted lines in Figure 5, which would be the same as the position seen in Figure 2 of the drawing. When the weight of a person is imposed on the platform, it is depressed to the position seen in full lines in Figure 5 of the drawing, and which, through the plunger 99, moves the lever 63a, and through the connecting rod 97 moves the dual pilot valves to the position seen in Figure 5 of the drawing. At this position of adjustment the compressed air is admitted through the duct 94 into the chamber 85, and thence through the duct 82 into the bottom of the chamber of the cylinder 16a, to cause the piston 20a together with the platform 24a to be raised, together with the person thereon, to a position as indicated diagrammatically in Figure 1 of the drawing.

When the piston approaches its upper limit of movement, it engages the lower end of the button 66a and operates the lever 63a in opposite direction, which in turn, through the spring connecting rod 97, shifts the dual pilot valve downwardly to seat the pilot valve 86, cutting off the supply of compressed air, and opening the pilot valve 87 so as to vent the cylinder 16a beneath the piston 28a, to atmosphere, and the compressed air therein is permitted to discharge through the duct 82, chamber 85, and through the pilot valve port 89. As the compressed air in cylinder 16a is discharged, the platform 24a is caused to move downwardly to the position seen in dotted lines in Figure 5.

When the platform and its piston arrive at its lower position of adjustment, the control mechanism is in condition ready to repeat the cycle of operation. In this connection it is to be understood that the coil spring 100 is of sufficient tension to resiliently support the weight of the platform 24a together with the connecting rod 27a and piston 28a in proper position so that the platform in response to the weight of a person

thereon, may be initially depressed a small amount, as above stated, from the dotted position to the full line position, for adjusting the control mechanism and initiating operation of the lift.

When a lift is to be mounted in the floor, immediately in front of the first step of the stair, the supporting bracket for the lift may be slightly modified to insure proper anchorage in position. If the floor is concrete or other material than wood, it may be necessary to provide suitable cavities therein for accommodating the lift associated with the first step, and also the lift in the floor in front of the first step.

It is to be understood that the platform may be 15 formed of substantial size, with the effective supporting area positioned to overlie the step proper. Furthermore the aligned projecting edge portion of the next adjacent upper step may be cut away to insure adequate clearance for the feet of the 20 person when the lift is in operation, and which also permit the use of a platform of greater width.

Although I have herein shown and described certain embodiments of my invention, it is to be understood to be illustrative only, as it is capable of modification and rearrangement of parts without departing from the spirit and scope thereof. I do not, therefore, wish to be understood as limiting this invention to the precise form herein disclosed, except as I may be so limited by the appended claims.

I claim as my invention:

1. A stair elevator comprising individual elevating units associated with each step of the stairs, each elevating unit comprising a horizontally disposed, vertically movable platform, an upright cylinder adapted to be connected to the underside of the stair beneath the said step, a piston mounted in the cylinder and having an upwardly projecting piston rod operably connected at its upper end to said platform, whereby said piston and platform are adapted to be moved vertically as a unit, the upper end of the cylinder being vented to atmosphere and the lower end being provided with inlet and outlet duct means, control means including valve means in the inlet duct for controlling communication of the cylinder, below the piston, with a source of compressed air, and valve means in the outlet duct for controlling venting of the bottom of the cylinder, below the piston, to atmosphere, and means actuated in response to pressure on the platform for operating said control means for causing opening of the valve means in the inlet duct and closing of the valve means in the outlet duct, whereby compressed air is supplied to the cylinder for raising said piston and platform for disposing the latter in substantially horizontal alignment with the adjacent upper step of the stair.

2. A stair elevator comprising individual elevating units associated with each step of the stairs, each elevating unit comprising a horizontally disposed, vertically movable platform, an upright cylinder adapted to be connected to the underside of the stair beneath the said step, a piston mounted in the cylinder and having an upwardly projecting piston rod operably connected at its upper end to said platform, whereby said piston and platform are adapted to be moved vertically as a unit, the upper end of the cylinder being vented to atmosphere and the lower end being provided with inlet and outlet duct means, control means including valve means

means in the inlet duct for controlling communication of the cylinder, below the piston, with a source of compressed air, and valve means in the outlet duct for controlling venting of the bottom of the cylinder, below the piston, to atmosphere, means actuated in response to pressure on the platform for operating said control means for causing opening of the valve means in the inlet duct and closing of the valve means in the outlet duct, whereby compressed air is supplied to the cylinder for raising said piston and platform for disposing the latter in substantially horizontal alignment with the adjacent upper step of the stair, and means engageable by the piston as the platform approaches such aligned position for actuating the control for causing closure of the valve means in the inlet duct and opening of the valve means in the outlet duct, and permitting said piston and platform to move downwardly to their lowered position of adjustment under control of the discharge of the compressed air in the cylinder to atmosphere.

3. A stair elevator comprising individual elevating units associated with each step of the stairs, each elevating unit comprising a horizontally disposed, vertically movable platform, an upright cylinder adapted to be connected to the underside of the stair beneath the said step, a piston mounted in the cylinder and having an upwardly projecting piston rod operably connected at its upper end to said platform, whereby said piston and platform are adapted to be moved vertically as a unit, the upper end of the cylinder being vented to atmosphere and the lower end being provided with inlet and outlet duct means, control means including valve means in the inlet duct for controlling communication of the cylinder, below the piston, with a source of compressed air, and valve means in the outlet duct for controlling venting of the bottom of the cylinder, below the piston, to atmosphere, means actuated in response to pressure on the platform for operating said control means for causing opening of the valve means in the inlet duct and closing of the valve means in the outlet duct, whereby compressed air is supplied to the cylinder for raising said piston and platform for disposing the latter in substantially horizontal alignment with the adjacent upper step of the stair, and means associated with said actuating means for resiliently supporting said piston and platform in their lowered position of adjustment.

4. A stair elevator comprising individual elevating units associated with each step of the stairs, each elevating unit comprising a horizontally disposed, vertically movable platform, an upright cylinder adapted to be connected to the underside of the stair beneath the said step, a piston mounted in the cylinder and having an upwardly projecting piston rod operably connected at its upper end to said platform, whereby said piston and platform are adapted to be moved vertically as a unit, the upper end of the cylinder being vented to atmosphere and the lower end being provided with inlet and outlet duct means, control means including valve means in the inlet duct for controlling communication of the cylinder, below the piston, with a source of compressed air, and valve means in the outlet duct for controlling venting of the bottom of the cylinder, below the piston, to atmosphere, means actuated in response to pressure on the platform for operating said control means for causing opening of the valve means in the in-

let duct and closing of the valve means in the outlet duct, whereby compressed air is supplied to the cylinder for raising said piston and platform for disposing the latter in substantially horizontal alignment with the adjacent upper step of the stair, means engageable by the piston as the platform approaches such aligned position for actuating the control for causing closure of the valve means in the inlet duct and opening of the valve means in the outlet duct, and permitting said piston and platform to move downwardly to their lowered position of adjustment under control of the discharge of the compressed air in the cylinder to atmosphere, and means associated with each of said inlet and outlet ducts for varying the flow of compressed air therethrough to vary the rate of speed of raising and lowering respectively of said piston and platform.

5. A stair elevator comprising individual elevating units associated with each step of the stairs, each elevating unit comprising a horizontally disposed, vertically movable platform, an upright cylinder adapted to be connected to the underside of the stair beneath the said step, a piston in the cylinder and having an upwardly projecting piston rod operably connected at its upper end to said platform, whereby said piston and platform are adapted to be moved vertically as a unit, the upper end of the cylinder being vented to atmosphere and the lower end being provided with inlet and outlet duct means, a master valve for controlling communication of the inlet duct with a source of compressed air and controlling venting of the outlet duct to atmosphere, said master valve being connected by duct means to the source of compressed air and operable thereby for controlling said inlet and outlet ducts, a normally closed pilot valve in said duct means to the master valve, and an operating member connected to said pilot valve and having a portion extending up through the bottom of the cylinder in position to engage said piston as it approaches its lower position of adjustment, whereby pressure on the platform moves the piston downwardly a small amount and moves the operating member to effect temporary opening of the pilot valve for moving the master valve and causing closure of the said outlet duct means and opening of the inlet duct means for admitting compressed air below the piston to elevate said piston and platform to dispose the latter substantially flush with the upper surface of the adjacent upper step.

6. A stair elevator comprising individual elevating units associated with each step of the stairs, each elevating unit comprising a horizontally disposed, vertically movable platform, an upright cylinder adapted to be connected to the underside of the stair beneath the said step, a piston in the cylinder and having an upwardly projecting piston rod operably connected at its upper end to said platform, whereby said piston and platform are adapted to be moved vertically as a unit, the upper end of the cylinder being vented to atmosphere and the lower end being provided with inlet and outlet duct means, a master valve for controlling communication of the inlet duct with a source of compressed air and controlling venting of the outlet duct to atmosphere, said master valve being connected by duct means to the source of compressed air and operable thereby for controlling said inlet and outlet ducts, a normally closed pilot valve in said duct means to the master valve, an

operating member connected to said pilot valve and having a portion extending up through the bottom of the cylinder in position to engage said piston as it approaches its lower position of adjustment, and spring means serving to hold the pilot valve closed and for yieldingly supporting the piston and platform at their lowered position of adjustment, whereby pressure on the platform moves the piston downwardly a small amount and moves the operating member to effect temporary opening of the pilot valve for moving the master valve and causing closure of the said outlet duct means and opening of the inlet duct means for admitting compressed air below the piston to elevate said piston and platform to dispose the latter substantially flush with the upper surface of the adjacent upper step.

7. A stair elevator comprising individual elevating units associated with each step of the stairs, each elevating unit comprising a horizontally disposed, vertically movable platform, an upright cylinder adapted to be connected to the underside of the stair beneath the said step, a piston in the cylinder and having an upwardly projecting piston rod operably connected at its upper end to said platform, whereby said piston and platform are adapted to be moved vertically as a unit, the upper end of the cylinder being vented to atmosphere and the lower end being provided with inlet and outlet duct means, a master valve for controlling communication of the inlet duct with a source of compressed air and controlling venting of the outlet duct to atmosphere, said master valve being connected by duct means to the source of compressed air and operable thereby for controlling said inlet and outlet ducts, a normally closed pilot valve in said duct means to the master valve, an operating member connected to said pilot valve and having a portion extending up through the bottom of the cylinder in position to engage said piston as it approaches its lower position of adjustment, whereby pressure on the platform moves the piston downwardly a small amount and moves the operating member to effect temporary opening of the pilot valve for moving the master valve and causing closure of the said outlet duct means and opening of the inlet duct means for admitting compressed air below the piston to elevate said piston and platform to dispose the latter substantially flush with the upper surface of the adjacent upper step, a normally closed second pilot valve in said duct means, and operating means connected to said second pilot valve and including a part projecting downwardly from the upper end of the cylinder and engageable by said piston as it approaches its upper limit of movement, for opening said second pilot valve and moving the master valve to a position for closing the inlet duct and venting the outlet duct to atmosphere for permitting the piston and platform to lower under control of the compressed air discharged through the outlet duct.

8. A stair elevator comprising individual elevating units associated with each step of the stairs, each elevating unit comprising a horizontally disposed, vertically movable platform, an upright cylinder adapted to be connected to the underside of the stair beneath the said step, a piston in the cylinder and having an upwardly projecting piston rod operably connected at its upper end to said platform, whereby said piston and platform are adapted to be moved vertically as a unit, the upper end of the cylinder

being vented to atmosphere and the lower end being provided with inlet and outlet duct means, a master valve for controlling communication of the inlet duct with a source of compressed air and controlling venting of the outlet duct to atmosphere, said master valve being connected by duct means to the source of compressed air and operable thereby for controlling said inlet and outlet ducts, a normally closed pilot valve in said duct means to the master valve, an operating member connected to said pilot valve and having a portion extending up through the bottom of the cylinder in position to engage said piston as it approaches its lower position of adjustment, whereby pressure on the platform moves the piston downwardly a small amount and moves the operating member to effect temporary opening of the pilot valve for moving the master valve and causing closure of said outlet duct means and opening of the inlet duct means for admitting compressed air below the piston to elevate said piston and platform to dispose the latter substantially flush with the upper surface of the adjacent upper step, a normally closed second pilot valve in said duct means, operating means connected to said second pilot valve and including a part projecting downwardly from the upper end of the cylinder and engageable by said piston as it approaches its upper limit of movement, for opening said second pilot valve and moving the master valve to a position for closing the inlet duct and venting the outlet duct to atmosphere for permitting the piston and platform to lower under control of the compressed air discharged through the outlet duct, spring means yieldingly urging the second pilot valve to closed position, and separate spring means yieldingly urging the first-mentioned pilot valve to closed position and acting on the operating member in a manner to yieldingly support the piston and platform at a lowered position of adjustment.

9. A stair elevator comprising individual elevating units associated with each step of the stairs, each elevating unit comprising a horizontally disposed, vertically movable platform, an upright cylinder adapted to be connected to the underside of the stair beneath the said step, a piston in the cylinder and having an upwardly projecting piston rod operably connected at its upper end to said platform, whereby said piston and platform are adapted to be moved vertically as a unit, the upper end of the cylinder being vented to atmosphere, and the lower end being provided with inlet and outlet duct means, a master valve for controlling communication of the inlet duct with a source of compressed air and controlling venting of the outlet duct to atmosphere, said master valve including a cylindrical chamber with which the inlet and outlet ducts connect, a separate pair of ports connected respectively to the supply of compressed air and to atmosphere, a cylindrical valve plug mounted for axial movement in the chamber and having two sets of ports for selectively completing communication of the inlet duct with the source of compressed air and for connecting the outlet duct to atmosphere, separate ducts for connecting the opposite ends of the valve chamber to the source of compressed air, a pilot valve in one duct including an operating member extending up into the bottom of the cylinder and moved by the piston when downward pressure is exerted on the platform, for opening the pilot valve for moving the master valve to close the outlet duct and open

5 the inlet duct to admit compressed air below the piston to raise the platform, and a second pilot valve in the other duct at the other end of the valve chamber, and operating means for said second pilot valve including a member projecting downwardly in the upper end of the cylinder and engageable by the piston as it approaches its upper limit of movement for causing opening of said second pilot valve and thereby moving the master valve to close the inlet duct and open 10 the outlet duct for venting the piston cylinder to atmosphere and permitting the piston and platform to move downwardly under control of the discharge of compressed air from the piston cylinder.

10. A stair elevator comprising individual elevating units associated with each step of the stairs, each elevating unit comprising a horizontally disposed, vertically movable platform, an upright cylinder adapted to be connected to the underside of the stair beneath the said step, a piston in the cylinder and having an upwardly projecting piston rod operably connected at its upper end to said platform, whereby said piston and platform are adapted to be moved vertically as a unit, the upper end of the cylinder being vented to atmosphere, a master control valve including a chamber provided at one end with a port in communication with a source of compressed air and a second port for venting to atmosphere, interconnected dual valve elements for alternately sealing said ports, a single duct communicating with said chamber and the bottom of the cylinder and adapted to serve as both an inlet and outlet duct, operating means for the dual valve elements including an abutment lever, a depending member on the platform, spring means for yieldingly supporting the platform at its lowered position of adjustment with the depending member in position to engage the lever and adapted to move the lever, when downward pressure is exerted on the platform, to move the dual valve member to open the port to compressed air supply and closing the port for venting to atmosphere, and an abutment member carried in the upper end of the piston cylinder in position to register with said lever, and having a part projecting into the cylinder in position to be engaged by the piston as it approaches its upper limit of 15 movement for moving the abutment member to actuate the lever in the opposite direction for reversing the dual valve to cause closing of the port to compressed air supply and opening the port for venting to atmosphere, whereby the air 20 below the piston is discharged to atmosphere to permit the piston and platform to move downwardly to its lower position of adjustment.

11. A stair elevator comprising individual elevating units associated with each step of the stairs, each elevating unit comprising a horizontally disposed, vertically movable platform, an upright cylinder adapted to be connected to the underside of the stair beneath the said step, a piston in the cylinder and having an upwardly projecting piston rod operably connected at its upper end to said platform, whereby said piston and platform are adapted to be moved vertically as a unit, the upper end of the cylinder being vented to atmosphere, a master control valve including a chamber provided at one end with a port in communication with a source of compressed air and a second port for venting to atmosphere, interconnected dual valve elements for alternately sealing said ports, a single duct communicating with said chamber and the bottom 25 30 35 40 45 50 55 60 65 70 75

of the cylinder and adapted to serve as both an inlet and outlet duct, operating means for the dual valve elements including an abutment lever, a depending member on the platform, spring means for yieldingly supporting the platform at its lowered position of adjustment with the depending member in position to engage the lever and adapted to move the lever, when downward pressure is exerted on the platform, to move the dual valve member to open the port to compressed air supply and closing the port for venting to atmosphere, an abutment member carried in the upper end of the piston cylinder in position to register with said lever, and having a part projecting into the cylinder in position to be engaged by the piston as it approaches its upper limit of movement for moving the abutment member to actuate the lever in the opposite direction for reversing the dual valve to cause closing of the port to compressed air supply and opening the port for venting to atmosphere, whereby the air below the piston is discharged to atmosphere to permit the piston and platform to move downwardly to its lower position of adjustment, and spring means for yieldingly maintaining the dual valve elements in either of its positions of adjustment.

12. A stair elevator comprising individual elevating units associated with each step of the stairs, each elevating unit comprising a horizontally disposed, vertically movable platform, an upright cylinder adapted to be connected to the underside of the stair beneath the said step, a piston in the cylinder and having an upwardly projecting piston rod operably connected at its upper end to said platform, whereby said piston and platform are adapted to be moved vertically as a unit, the upper end of the cylinder being vented to atmosphere, a master control valve including a chamber provided at one end with a port in communication with a source of compressed air and a second port for venting to atmosphere, interconnected dual valve elements for alternately sealing said ports, a single duct communicating with said chamber and the bottom of the cylinder and adapted to serve as both an inlet and outlet duct, operating means for the dual valve elements including an abutment lever, a depending member on the platform, spring means for yieldingly supporting the platform at its lowered position of adjustment with the depending member in position to engage the lever and adapted to move the lever, when downward pressure is exerted on the platform, to move the dual valve member to open the port to compressed air supply and closing the port for venting to atmosphere, an abutment member carried in the upper end of the piston cylinder in position to register with said lever, and having a part projecting into the cylinder in position to be engaged by the piston as it approaches its upper limit of movement for moving the abutment member to actuate the lever in the opposite direction for reversing the dual valve to cause closing of the port to compressed air supply and opening the port for venting to atmos-

phere, whereby the air below the piston is discharged to atmosphere to permit the piston and platform to move downwardly to its lower position of adjustment, and separate adjustment means associated with said single duct for varying independently of each other the flow of air into and out of the cylinder for controlling the speed of raising or lowering of the piston and platform.

13. A stair elevator comprising individual elevating units associated with each step of the stairs, each elevating unit comprising a horizontally disposed, vertically movable platform, an upright cylinder adapted to be connected to the underside of the stair beneath the said step, a piston in the cylinder and having an upwardly projecting piston rod operably connected at its upper end to said platform, whereby said piston and platform are adapted to be moved vertically as a unit, the upper end of the cylinder being vented to atmosphere, means for resiliently supporting the piston and platform at their lowered position of adjustment, a master control valve including a chamber provided at one end with a port in communication with a source of compressed air and a second port for venting to atmosphere, interconnected dual valve elements for alternately sealing said ports, a single duct communicating with said chamber and the bottom of the cylinder and adapted to serve as both an inlet and outlet duct, operating means for the dual valve elements including an abutment lever, a depending member on the platform, spring means for yieldingly supporting the platform at its lowered position of adjustment with the depending member in position to engage the lever and adapted to move the lever, when downward pressure is exerted on the platform, to move the dual valve member to open the port to compressed air supply and closing the port for venting to atmosphere, and an abutment member carried in the upper end of the piston cylinder in position to register with said lever, and having a part projecting into the cylinder in position to be engaged by the piston as it approaches its upper limit of movement for moving the abutment member to actuate the lever in the opposite direction for reversing the dual valve to cause closing of the port to compressed air supply and opening the port for venting to atmosphere, whereby the air below the piston is discharged to atmosphere to permit the piston and platform to move downwardly to its lower position of adjustment.

14. For use with a conventional stairway including a series of vertically spaced steps, a series of fluid operated lifts, operable by a source of fluid under pressure, one lift being associated with each step and including a horizontally disposed platform, and control means operable in response to the weight of a person on the platform to effect raising of the latter to a position substantially flush with the next adjacent upper step.
